Primary Examiner — Jack Reickel

CLAIM

The ornamental design for a display screen with a graphical user interface, as shown and described.

DESCRIPTION

The FIGURE is a view of a display screen with a graphical user interface.

The long-short-long-dashed broken line is included for the purpose of illustrating a display screen and forms no part of the claimed design. The evenly-dashed broken line is included for the purpose of illustrating a graphical user interface and forms no part of the claimed design.
